UNITED STATES PATENT OFFICE.

TELESPHORE C. DEMERS, OF SPRINGFIELD, VERMONT.

WARP-TENSION EQUALIZER FOR LOOMS.

Application filed January 13, 1926. Serial No. 81,008.

This invention relates to let-offs for looms and more particularly to a warp tension equalizing means for effecting an even let-off of the warp as distinguished from a sudden and jerky let-off.

It is a well known fact that in looms embodying a let-off mechanism consisting of a system of levers and friction shoes frictionally engaging the heads of the warp beam together with weights for imposing tension on the shoes through the lever systems, a sudden tension is imposed upon the warp threads with the result that the warp is let off with a sudden and jerky motion and, consequently, the cloth is unevenly woven and, therefore, has thick and thin places. Where such cloth is sheared, the fly blade of the shearing machine acts upon the thicker places in the cloth in a manner to cut or shear the same to a greater degree than where the fly blade acts upon a thinner portion of the cloth, so that the cloth has a cloudy appearance and its commercial value is reduced. Likewise, where lets-off are employed embodying weights to impose the required tension on the friction shoes which coact with the heads of the warp beam, the weight supporting rods are liable to be disturbed by objects coming in contact therewith, as for example, the carrying of warp beams past the loom, and, as a consequence, a thin place is formed in the cloth, delaying the operation of the loom and frequently causing smash-ups. In consideration of the foregoing, it is the general object of the invention to provide a warp tension equalizer or let-off which will be so constructed and function in such a manner as to insure of the warp being let off evenly and with a more or less steady motion, thereby avoiding the disadvantages attending the operation of a let-off which permits the warp to have a jerky motion, the invention contemplating at the same time, the provision of a let-off of warp tension equalizer which will be adjustable to permit of the desired tension being imposed upon the warp to insure of proper weaving and the production of cloth of uniform texture throughout.

Another disadvantage attending the use of let-off mechanisms embodying weights, is that these weights are ordinarily of one pound each and a fine adjustment of the tension disposed upon the friction shoes cannot be obtained and, therefore, the pres-

ent invention has a further object to provide means whereby an extremely fine adjustment may be obtained depending upon the character of the cloth or other material to be woven. 60

Another object of the invention is to provide a let-off which may be readily and quickly adjusted to permit of the removal of the friction shoes when changing warp beams and without disturbing the adjustment of that portion of the let-off mechanism which serves to equalize the tension on the warp. 65

In the accompanying drawings:

Figure 1 is a front elevation of one of 70 the equalizers and the adjacent end of the warp beam.

Figure 2 is a vertical sectional view taken substantially on the line 2—2 of Figure 1, looking in the direction indicated by the 75 arrows.

Figure 3 is a view partly in side elevation and partly in section, illustrating in detail the equalizer embodying the invention. 80

Figure 4 is a top plan view of the equalizer, parts being shown in section. 80

Figure 5 is a view partly in section and partly in front elevation in detail.

Figure 6 is a vertical transverse sectional view in detail, taken substantially on the line 85 6—6 of Figure 3, looking in the direction indicated by the arrows.

Figure 7 is a detail vertical transverse sectional view taken substantially on the line 90 7—7 of Figure 4, looking in the direction indicated by the arrows.

Figure 8 is a detail view in side elevation, illustrating a portion of the equalizer and showing a latch member constituting a part 95 thereof, swung to releasing position.

Figure 9 is a view in side elevation, of the bearing for the warp beam.

In the drawings, the numeral 1 indicates one side of the rear end of the loom frame structure which, of course, may be of any desired or standard formation, and each side member of the said frame structure supports an integral fixed bearing section, indicated by the numeral 2, provided with a semi-circular recess 3 matching with a recess 4 of 100 corresponding shape formed in the opposing face of a bearing section 5 which is pivoted at its lower end, as at 6, to the section 2 and is normally held in a closed or upright position by means of a threaded stem 7 which is 105 connected with the section 2 and onto which is threaded a nut 8 bearing against the rear 110

side of the section 5, the circular openings provided by the recesses 3 and 4 accommodating the corresponding trunnions 9 of the warp beam 10, the head of the warp beam 5 being indicated by the numeral 11, it being understood that only one end of the warp beam and one side of the frame structure is disclosed in the drawings, as these parts, as well as the tensioning equalizing mechanism 10 embodying the invention, are duplicated at the opposite side of the loom. The numeral 12 indicates the usual whip roll which is located above the warp beam and over which the warp threads are passed to the harness 15 of the loom.

Generally speaking, the invention may be said to comprise a tensioning means for the warp beam and an equalizing or shock absorbing means associated therewith. The 20 tensioning means is associated directly with each head of the warp beam and includes a friction shoe indicated in general by the numeral 13, which consists of an arcuate body member 14 to the concave side of which 25 are secured a number of friction strips 15 of any metal found suitable for the purpose, flush or countersunk screws 16 being preferably employed for this purpose. One end of the body member 14 of the friction shoe is 30 provided with an outstanding lug 17 which is formed with a notch 18, and to the other end of the said body member 14, at the outer side thereof, there is riveted a steel band 19 which is provided with a lining 20 of leather 35 or any other suitable friction material, the band being more or less flexible. The shoe body 14 encompasses the upper side of the respective head of the warp beam, and the band 19 extends about the remainder of the 40 circumference of the said head and is provided at its free end with eyes 21 which accommodate the end portions of a transverse pin 22 carried by a stem 23 which is engaged in the notch 18 in the lug 17 and is threaded, as at 24, for the application thereto of a 45 wing nut 25, a compression spring 26 being arranged upon the stem and bearing at one end against a washer 27, in turn bearing against the upper side of the lug 17 and at its other end bearing against a washer 28 50 which is engaged by the said wing nut 25, it being understood that by adjusting the wing nut, against the tension of the spring 26, the friction unit as a whole may be suitably tightened about the head of the warp beam 55 so as to frictionally resist rotative movement of the said beam. A means similar to the tensioning means disclosed has heretofore been employed as a substitute for a tensioning mechanism embodying weights, but the 60 fact remains that, in the operation of the loom, a jerky movement is imparted to the warp with the undesirable result above outlined. Therefore, as previously stated, it is the primary object of the present invention 65 to eliminate this sudden and jerky let-off of

the warp and provide for an even and steady let-off.

The body member 14 of the friction shoe 13 is provided upon its upper side, substantially midway between its ends, with an 70 upstanding yoke 29, the side members of which are indicated by the numeral 30, and said side members are formed with recesses 31 which open through their forward sides and the inner ends of which recesses are 75 of substantially semicircular form so as to accommodate studs 32 which extend in opposite directions from the sides of a sleeve 33 which is disposed between the said side members 30 of the yoke. In order that the 80 studs 32 may be retained within the bearing ends of the recesses 31, a retaining latch 34 is mounted for pivotal movement upon a dowel pin 35, upon the outer side of each 85 of the members 30 of the yoke 29 and each latch 34 is formed at one side with a boss 36, the edge of which is concentric to the respective dowel pin 35, and upon the corresponding edge of each latch there is provided a finger 37 which is spaced with relation to the said boss 36 so as to provide a 90 recess 38, the inner end wall of which is of concave form to embrace one side of the shank of a securing screw 39 which is threaded into an opening 40 in the corresponding side member of the yoke. The finger 37 of each latch 34 is spaced inwardly from the free end of the latch, and one edge of the finger merges with the said edge of the latch on the arc of a circle, as indicated by the numeral 41, so as to partly embrace the respective stud 32 when the latch is 95 swung upwardly to the position shown in full lines in Figure 3 and the dotted lines in Figure 8, it being evident that when the latch is in this position and the corresponding screw 39 is tightened, the latch will be so held as to retain the respective stud 32 in the recess 31. It will be evident, on the other hand, that by loosening the screw 39, the latch may be swung downwardly substantially to the position shown in full lines in Figure 8, whereby to disengage from the respective stud 32. Therefore, by loosening the 100 screws 39, the two latches may be 105 swung downwardly so as to free the studs 32 and permit separation of the sleeve 33 from the yoke, or vice versa. It will also be evident by reference to Figure 8, that the boss 36 is at all times engaged behind the head of the respective securing screw 39, so that the latch cannot become disengaged from its pivot pin 35. The purpose of this arrangement and construction of the parts 110 will presently be more fully explained.

The numeral 42 indicates a barrel which is fitted through the bore of the sleeve 33 and which is exteriorly threaded from one end for a suitable portion of its length, as indicated by the numeral 43. A nut 44 is 115 120 125 130

threaded onto the barrel and bears at one end against one end of the sleeve 33, and a nut 45 is likewise threaded onto the barrel and bears against one end of a spacing sleeve or collar 46 which in turn, bears against the other end of the sleeve 33, so that by loosening the nuts 44 and 45 and suitably adjusting the same, the barrel may be suitably adjusted through the sleeve 33 and secured in the desired position of adjustment. The numeral 47 indicates a plunger stem which is fitted through the bore of the barrel 42 and has fixed upon one of its ends a hand wheel 48 through the medium of which it may be manually rotated, the hand wheel bearing numbers indicated by the numeral 49, upon its periphery, for a purpose to be presently explained. The plunger stem 47 is threaded from its end which carries the hand wheel 48, for a suitable portion of its length, as indicated by the numeral 50, and the barrel 42 is interiorly threaded for a portion of its length as indicated by the numeral 51, so that the plunger stem may be adjusted longitudinally within the barrel by rotating the same through the medium of the said hand wheel. A hand wheel 52 having an interiorly threaded hub 53, is fitted onto the threaded portion of the plunger stem 47 and, after the plunger stem has been rotated to obtain the desired adjustment, as will be presently explained, the said hand wheel 52 may be rotated so as to cause its hub to bind against the adjacent end of the barrel 42, thereby locking the said plunger stem in its position of adjustment. At this point, it will be observed that the unthreaded end of the plunger stem projects a short distance beyond the corresponding end of the barrel 42.

The numeral 54 indicates a supporting bearing member which is preferably formed from a one-piece metal blank bent or otherwise shaped to provide spaced side members 55 and a laterally disposed bearing which comprises right angular upper and lower extensions 56 and 57 of the side members 55, these extensions being joined by a connecting portion 58 which is of substantially 50 semicircular shape in cross section so as to accommodate one side of the unthreaded portion of the barrel 42. The said member 54 is fixedly supported by being mounted upon any suitable fixed part of the frame work of the loom as for example a bracket member 59, which may extend from one of the side members 1 and which is received between the side members 55 of the said member 54, a bolt 60 being secured through the said side members 55 and the said bracket member 59, as clearly shown in Figure 7 of the drawings. A retaining block 61 is fitted between the upper and lower extensions 56 and 57 and one side of this block 65 opposes the inner side of the connecting portion 58 of the bearing member and lightly engages the adjacent side of the barrel 42 so that the said barrel may have sliding movement through the bight of the bearing member. The block 61 is secured in place by means of a set bolt 62 which is fitted through a slot 63 formed in the upper portion 56 of the bearing member and threaded into the upper side of the block 61, it being understood that by loosening the set bolt, the block 61 may be adjusted away from the barrel 42 so as to permit displacement of the barrel laterally in the bearing member, and this is done when it becomes necessary to dismount the barrel and parts associated therewith and at the time the latches 34 are adjusted so as to release the studs 32 upon the sleeve 33 and at the time the warp beams are substituted one for another. The bearing member 54 supports an abutment member which is indicated in general by the numeral 64 and which is preferably formed from a single blank of sheet metal which is fashioned to provide spaced side portions 65 and a connecting portion 66. The spaced side portions 65 are formed with openings 67 and the said abutment member is so arranged that its side portions 65 will extend one beside the outer side of one of the side members 55 of the bearing member 54, and the other beside the bight portion 58 of said bearing member with the opening 67 in the first mentioned side portion 65 located opposite the threaded opening 68 in the first mentioned side member 55 and with the opening 67 in the second mentioned side portion 65 located opposite a threaded opening 69 in the said bight portion 58. A bolt 70 is fitted through the opening 67 in the first mentioned side portion 65 of the abutment member and threaded into the opening 68 in the bearing member 54, and a similar bolt 71 is fitted through the opening 67 in the other side portion of the abutment member and threaded into the opening 69, the said bolt 71 having a reduced unthreaded end portion 72 which engages in a slot 73 formed in the side of the barrel 42. The engagement of the end 72 of the bolt 71 in the slot 73 in the barrel 42 serves to limit the sliding movement of the barrel under operating conditions presently to be explained. In order to provide against any displacement of the abutment member 64, dowel pins 74 are fitted through openings in the side portions 65 of the said abutment member and into openings formed in the adjacent portions of the bearing member 54. It will be observed that the connecting portion 66 of the abutment member 64 extends transversely opposite the laterally disposed bearing of the bearing member 54 and, therefore, directly in the path of movement of the plunger stem 47, the unthreaded end of which projects beyond the end of the 125 130

barrel 42, being presented to the said connecting portion of the abutment member and being adjustable with relation thereto through rotation of the plunger stem.

5 A washer 75 is arranged upon the barrel 42 against the nut 44 and a similar washer 76 is arranged upon the barrel against the adjacent side of the lateral bearing of the bearing member 54, and an equalizing spring 10 of the compression type, indicated by the numeral 77, is arranged upon the barrel and bears against said washers 75 and 76, the tendency of the spring being to shift the barrel in a direction away from the bearing 15 member in which its unthreaded end is received. If desired, a portion of the bracket 59 may be arranged to extend upwardly into the space between a part of the connecting portion 66 of the abutment member and the 20 opposing portion of the bearing member 54, as shown in Figure 2.

It is a well known fact that in the operation of a loom embodying merely a tensioning means for the warp beam such as the 25 friction means hereinbefore described, the operation of the take-up motion at the front of the loom, the beating up of the lay, and the opening and closing of the shed are likely to cause a jerky pull upon the warp at the 30 time of passage of the shuttle through the shed but while the friction tensioning means is intended to compensate for this jerky pull and maintain the warp suitably tensioned, this is not, in fact, always accomplished, and as a result the product is of an 35 inferior quality. It is with the object in view of overcoming this disadvantage and maintaining the warp tensioned at all times, that the equalizing mechanism embodying 40 the invention and hereinbefore described, has been devised, this being accomplished by providing for equalization of the tension on the warp between the take-up and let-off motions, so that when the lay beats up against 45 the cloth, the warp will be under a desired degree of tension in accordance with the character of the woven material to be produced and whether it be light or heavy or loosely or closely woven.

50 In the operation of the loom, equipped with the warp tension equalizer embodying the invention, the plunger stem 47 is first rotated through the medium of the hand wheel 48 until, by observing the indicating 55 numerals upon the periphery of the hand wheel, the loom fixer has adjusted the plunger stem to bring the unthreaded abutment end thereof to a position spaced from the abutment 66 a distance equal to the distance 60 of movement of the warp at each pick of the loom, as previously determined, as for example, one twenty-sixth of an inch, and the hand wheel 52 is then adjusted to lock the plunger stem in its position of adjustment. At the moment the take-up motion

operates to exert a pull upon the warp, a corresponding rotative movement will be imparted to the friction shoe 13 and band 19 against the tension of the spring 77 and until the said end of the plunger stem is in engagement with the said abutment 66. At this moment, the rotation of the warp beam is frictionally resisted by the shoe 13 and friction band 19. At this time, the shuttle is about to pass through the shed, and as the 70 harnesses are moved to open the shed, the warp is relieved of the tension to which it was subjected by the take-up motion, and the equalizer spring 77, which is at this time still under tension, immediately acts to shift the barrel 42 in a rearward direction, thereby imparting rotary motion to the warp beam to an extent sufficient to suitably tension the warp, this rearward movement of the barrel 42 being limited by the engagement 80 of the forward end of the slot 73 against the reduced end 72 of the bolt 71. It will be evident at this point that while the rearward movement of the plunger is limited by the engagement of the said end wall of the slot with the reduced end of the said bolt, this is entirely independent of the forward movement of the plunger stem 47 in unison with the said barrel, as the extent of this movement is regulated in accordance 85 with the adjustment of the said plunger stem and the distance between its abutting end and the abutment 66. It will now be evident that not only is the sudden pull which is exerted upon the warp at the moment of operation of the take-up motion rendered more even and gradual than in instances where the ordinary types of let-offs are employed, but likewise, after the shuttle has passed through the shed and the shed is 90 about to close, the warp is suitably tensioned through the action of the equalizer spring 77, thereby resulting in a very uniform weaving of the cloth or other material without any liability whatsoever of any inequalities or thin places appearing in the finished product.

As before stated, the plunger stem 47 may be adjusted so as to position the engaging or abutting end thereof at any desired distance 105 spaced from the abutment 66, the numerals which are upon the periphery of the adjusting hand wheel 48 permitting the loom fixer to determine with a greater or less degree of accuracy the degree of adjustment, and by 110 adjusting the said plunger stem, the tension equalizer embodying the invention may be adapted for operation of the loom in connection with which it is employed, to weave fabrics of various kinds. Thus, while a slow 115 operating harness motion is generally accepted by the loom fixer as the one to be preferred, the tension equalizer embodying the invention may be equally as well adapted to operate where a faster operation of the har- 120

ness is preferred. It will, therefore, be evident that the tension equalizer embodying the invention is adapted for universal application and that it may be applied to looms 5 of various types to great advantage.

In the specific example of adjustment given above, the engaging end of the plunger stem has been adjusted to occupy a position spaced approximately one twenty-sixth of 10 an inch from the abutment 66, but in some mil's, cotton warp and shoddy fillings are used and inasmuch as there is but little yield in cotton warp, the said plunger stem is, under these conditions, adjusted to bring its 15 engaging end to position approximately a quarter of an inch from the abutment, so that the plunger will move a greater distance at the time of operation of the take-up motion of the loom than would otherwise be 20 necessary or desirable, inasmuch as the filling of shoddy is very uneven and lumpy. Likewise, when weaving material which has no property of extensibility, such for example as the weaving of wire screen material, the plunger stem will be adjusted so as 25 to space its engaging end a maximum distance from the abutment 66. On the other hand, where the material is to be loosely woven and there are, for example, fourteen 30 picks of the loom per inch of material, and but little tension is required to maintain the warp sufficiently taut, the plunger rod 47 will be so adjusted as to bring its abutment end directly in contact with the abutment 66, 35 under which conditions, the equalizer is rendered inactive except that it then constitutes a rigid holding means for the friction assemblage comprising the shoe 13 and friction band 19, and tension is imposed solely 40 through the medium of the spring 26 which, under the previously described conditions, serves its usual purpose.

The spring 77, which serves to equalize the tension on the warp after it has been moved 45 by the operation of take-up motion, may be a metal spring or it may be of leather or rubber, depending entirely upon the character of the material to be woven, and it 50 may have the cross sectional contour of any of the well known types of springs.

It will be evident from the foregoing description that, after the equalizer mechanism has been once adjusted in accordance with the character of the material to be woven 55 and likewise in accordance with the pick of the loom which is to prevail during the operation thereof, no further attention need be given the said mechanism, it being merely necessary for the attendant at the loom to 60 adjust the tension of the spring 26 when a full warp beam is substituted for an exhausted one.

It will also be evident from the foregoing description that the substitution of a full warp beam for an exhausted one may be

readily accomplished by loosening the set bolt 62, shifting the block 61 away from the barrel 42 to permit of lateral displacement of the barrel to clear the end 72 of each bolt 71 and loosening the set bolt 39 to permit of dropping of the latches 34 to permit of relative separation of the tension equalizer and the friction shoe 13. 70

It will be understood that the equalizer spring 77 will be so tensioned that it will 75 yieldably resist movement of the tension unit comprising the shoe 13 and band 19, in the initial action of the let-off mechanism and until the abutting end of the plunger stem 47 has been brought into engagement with 80 the abutment 66, whereupon this resistance will be overcome to permit of rotative movement of the warp beam against the resistance offered by the said friction unit, with a final backward movement of the warp beam 85 and friction unit under the influence of the said spring 77.

Having thus described the invention, what I claim is:

1. In a let-off mechanism for looms, the 90 combination with the warp beam, of a frictional tension unit coacting with the head thereof and means coacting with the tension unit for yieldably resisting movement of the tension unit together with the warp beam, 95 said means comprising a barrel mounted upon the said unit, a plunger stem adjustably threaded in the barrel and having an abutment end projecting beyond one end of the barrel, a spring coacting with the barrel and yieldably resisting movement of the said barrel in the direction to permit of movement of the tension unit together with the warp beam, means for positively resisting movement of the said plunger stem comprising 100 an abutment positioned for engagement by the plunger stem when the same has been moved through the let-off pull of the warp from the beam, said spring constituting 105 means for reversely moving the said beam through the medium of the said barrel and tension unit to tension the warp. 110

2. In a let-off mechanism for looms, the 115 combination with the warp beam, of a frictional tension unit coacting with the head thereof, a barrel upon a member of the said unit, a bearing for one end of the barrel, a plunger adjustably fitted in the barrel and having an abutment end projecting beyond the said end of the barrel, an abutment upon the bearing for engagement by the said end of the plunger, and a spring upon the barrel coacting therewith to urge the same in one direction, the said spring constituting means, 120 acting through the barrel, for yieldably resisting movement of the tension unit together with the warp beam and for reversely moving the said unit and beam after the let-off pull of the warp and when the warp beam 125 is relieved of tension, the engagement of the 130

plunger against the abutment acting to positively resist movement of the said unit during the let-off movement of the warp beam.

3. In a let-off mechanism for looms, the combination with the warp beam, of a frictional tension unit coacting with the head thereof, a bearing member supported upon a member of the said unit, a barrel adjustably fitted through the said bearing member for longitudinal adjustment, a second bearing for one end of the barrel, a plunger adjustably fitted in the barrel and having an abutment end projecting beyond the said end of the barrel, an abutment upon the last mentioned bearing for engagement by the said end of the plunger, and a spring upon the barrel coacting therewith to urge the same in one direction, the spring constituting means, acting through the barrel, for yieldably resisting movement of the tension unit together with the warp beam and for reversely moving the said unit and beam after the let-off pull of the warp and when the warp is relieved of tension, the engagement of the plunger against the abutment acting to positively resist movement of the said unit during the let-off movement of the warp beam.

4. In a let-off mechanism for looms, the combination with a warp beam, of a frictional tension unit coacting with the head thereof, a bearing member supported upon a member of the said unit, a barrel adjustably fitted through the said bearing member for longitudinal adjustment, a second bearing for one end of the barrel, a plunger adjustably fitted in the barrel and having an abutment end projecting beyond the said end of the barrel, an abutment upon the last mentioned bearing for engagement by the said end of the plunger, a spring upon the barrel coacting therewith to urge the same in one direction, the spring constituting means, acting through the barrel, for yieldably resisting movement of the tension unit together with the warp beam and for reversely moving the said unit and beam after the let-off pull of the warp and when the warp is relieved of tension, the engagement of the plunger against the abutment acting to positively resist movement of the said unit during the let-off movement of the warp beam, and means for limiting the movement of the barrel in the direction in which it is urged by the said spring.

5. In a let-off mechanism for looms, the combination with the warp beam, of a frictional tension unit coacting with the head thereof, a bearing member supported upon a member of the said unit, a barrel adjustably fitted through the said bearing member for longitudinal adjustment, a second bearing for one end of the barrel, a plunger adjustably fitted in the barrel and having an abutment end projecting beyond the said

end of the barrel, an abutment upon the last mentioned bearing for engagement by the said end of the plunger, a spring upon the barrel coacting therewith to urge the same in one direction, the spring constituting means, acting through the barrel, for yieldably resisting movement of the tension unit together with the warp beam and for reversely moving the said unit and beam after the let-off pull of the warp and when the warp is relieved of tension, the engagement of the plunger against the abutment acting to positively resist movement of the said unit during the let-off movement of the warp beam, and means for limiting the movement of the barrel in the direction in which it is urged by the said spring, the said means comprising a stop element carried by the second mentioned bearing, the said barrel having a slot accommodating the said stop element.

6. In a let-off mechanism for looms, the combination with the warp beam, of a frictional tension unit coacting with the head thereof and including a shoe engaging the upper side of the said head and a friction band connected with the shoe, and spring means connecting the other end of the band and shoe to tension the shoe and band about the head, a yoke upon the shoe including spaced side members, a bearing sleeve having studs mounted in the spaced side members of the yoke, the said side members of the yoke having recesses opening through one side thereof to accommodate said studs and provide for engagement and disengagement of the studs with and from the said yoke, releasable latch members mounted upon the said sides of the yoke and adjustable into and out of position to close the said openings in the side members of the yoke and engage the said studs to retain the same in the said openings in the said side members, a barrel fitted through the said bearing and adjustable longitudinally therein, means for holding the barrel in positions of adjustment, a plunger adjustably fitted in the barrel and having an abutment end projecting beyond one end of the barrel, an abutment for engagement by the said end of the plunger, and a spring upon the barrel coacting therewith to urge the same in one direction, the said spring constituting means, acting through the barrel, for yieldably resisting movement of the tension unit together with the warp beam and for reversely moving the said unit and beam after the let-off pull of the warp and when the warp is relieved of tension, the engagement of the plunger against the abutment acting to positively resist movement of the said unit during the let-off movement of the warp beam.

In testimony whereof I affix my signature.
TELESPHORE C. DEMERS. [L. s.]
